ATTORNEY.

UNITED STATES PATENT OFFICE.

OWEN M. BANGS, OF BROOKLYN, NEW YORK.

SEAL LOCK.

Application filed December 4, 1926. Serial No. 152,598.

The invention relates to a device for sealing locks, particularly trunk locks of the swinging hasp type, although the invention is applicable also to other types of locks.

5 The principal object of the invention is to provide means whereby trunks, suit cases, or other baggage, may be protected against undetected and unauthorized opening. At present, baggage may be opened at will by 10 a clever thief having a master key or possessed of a few simple tools, and no trace of the theft remains. With my improved seal, such undetected tampering is rendered impossible. The invention may be applied 15 to baggage of all kinds, boxes, bags, freight cars and many other uses.

A further object of the invention is to provide an improved means for fastening a lock to baggage or other articles, whereby its 20 removal from the outside by means of a chisel or like tool is rendered impossible, or at least much more difficult than at present. By the combination of this securing means with the improved sealing device, undetected 25 theft may be to a large extent, eliminated.

The invention will be more clearly understood by reference to the accompanying drawings in which are shown an illustrative embodiment of the invention, in which:—

30 Fig. 1 is a front elevation showing a trunk lock of the swinging hasp type to which the improved sealing device is applied.

Fig. 2 is a central longitudinal sectional view of the same.

35 Fig. 3 is a transverse section on line 3—3 of Fig. 1, showing the fastening means for the fixed plate of the hasp lock.

Fig. 4 is a view, partly in longitudinal section and partly in elevation, showing the 40 lock equipped with the improved seal, preparatory to being closed.

Fig. 5 is a view partly in elevation and partly in section on line 5—5 of Fig. 2, showing the attachments to the ordinary 45 lock, including a pin, disk and seal assembled upon the movable member of the lock, which is shown within its keeper.

Fig. 6 is a view on line 6—6 of Fig. 2 showing the disk upon which is mounted the 50 seal.

Fig. 7 is a view similar to Fig. 4, but showing the lock removed from its keeper after the seal has been broken.

55 Figs. 8, 9 and 10 are views showing various forms of the seal.

In the drawings the reference character A denotes generally the plate member of a trunk lock of the swinging hasp type which is adapted to be permanently secured to one portion B of a trunk, or other article. To 60 the plate is hinged a movable hasp member C of any desired type, which is provided with the usual cylindrical casing or lock housing D, provided with bolts E, adapted to be operated by a key (not shown) inserted 65 in the key hole F. A keeper or shell G is secured to a portion H of the trunk, and is adapted to receive the lock housing D of the swinging hasp member.

According to my invention, the outer face 70 10 of the swinging hasp member is provided with a pair of slits 11—11, on opposite sides of and in alignment with the keyhole F, in order to permit the insertion of the ends of a seal 12. On the inner face 13 of the lock 75 housing D is mounted a pin 14, permanently secured thereto, and provided with a bowed spring, 15, mounted on the pin. Upon the outer end of the pin, a disk 16 is removably mounted, and over this disk the ends of the 80 seal 12 pass, these ends being provided with holes 17—17 which fit the pin 14 and hold the seal in position. The seal is likewise provided with a boss 18, adapted to fit within the keyhole F. The spring 15 engaging the 85 disk 16 serves to hold the seal taut, and prevents its removal from over the keyhole without breaking the seal. Each seal used is provided with a serial number for the purpose of identification. The seal may be 90 of any desired material, preferably metal, although a strong paper seal may be used if desired. The seal having been assembled, as shown in Fig. 4, the lock is snapped into its keeper, the tumblers E engaging shoulders 95 K of the keeper member in the usual manner as shown in Fig. 2.

Within the shell of the keeper G are provided a plurality of spring detents 19, shown as two in number, having cam faces 20 over 100 which the edge of the disk 16 is forced by means of the bowed spring 15, the disk being then held in place by means of the shoulders 21 of said detents.

The lock being now in position, as shown 105 in Fig. 2, it cannot be opened without breaking the seal 12 in order to give access to the key hole F.

It will be further noted that even though the bolts E should not function, the hasp 110

would be held in latched position by the disk 16 and detents 19, and could not be opened without breaking the seal 12. Thus, if desired, the key and tumblers may be dispensed with entirely, and only the improved sealing device employed, the invention being applicable in either case.

In order to release the lock, the seal is broken, and the key operated to release the 10 bolts E. The lock member is now withdrawn, as shown in Fig. 7, carrying with it the pin 14 and spring 15, but leaving the disk 16 within the shell or keeper. In order to release the disk it is merely rotated a 15 short distance until notches 21 meet the detents 19, whereupon the disk is withdrawn and is replaced upon the pin 14 together with a new seal.

The sealing device renders it impossible 20 to separate the lock from its keeper without detection. However, where the ordinary form of hasp lock is employed a thief may remove the keeper G and plate A by merely cutting the bolts or rivets by means of 25 which they are attached to the trunk. These fastening devices are readily replaced, and detection of the theft is delayed. Also, the hinge between the plate A and hasp C is readily tampered with by merely driving out 30 the usual hinge pin. In order to render undetected theft impossible, I have provided a special form of hinge, and a special fastening means for the keeper G and for the fixed plate A, these features combining with my 35 improved seal to accomplish the main object of my invention.

As shown in Figs. 1 and 3, the fixed plate A is formed of two parts 23, 24, each provided with a portion of the hinge, as 25, 26, and 40 each having integral therewith a threaded stem 27—27 adapted to be passed through the trunk wall B, and fastened in place by means of a nut 28, the plates 23, 24, having an over-lapping fit as shown at 29. The 45 meeting portions 29 are preferably beveled and overlaped, though any form of cut which will provide an overlapping of these portions will suffice, the purpose being to prevent the insertion of any instrument between the parts 23—24.

Upon the member C is formed a portion 30 of the hinge which is provided with a pin 31, which may be removable, if desired, and which extends beyond the portion 30 and 55 into the ears 25, 26 of the plate members 23, 24. However, the ends of the members 25, 26 are closed, thereby preventing access to the pin 31, which is entirely out of view, and inaccessible. Likewise, the bolts 27, 27 60 are covered by the plates 23, 24 and cannot be cut.

In a like manner, the keeper G is provided with integral threaded stems 32 formed on plate 33 which surrounds the inner shell. 65 When the stems 32 are passed through the

trunk wall H and capped with nuts as shown in Fig. 5 they are entirely invisible from the outside, as well as inaccessible.

An article equipped with my improved seal and lock fastening means is rendered 70 practically immune from undetected theft. The invention has been described in detail for the purpose of illustration, but it will be understood that various modifications may be employed without departing from the 75 spirit of the invention.

Having thus described my invention, what I claim as new and desire to secure by Letters Patent is:—

1. The combination with a removable cylindrical lock member and a fixed keeper shell adapted to receive said lock member, of a pin extending inwardly from said lock member when in assembled position, a movable plate mounted upon said pin, a seal passing around said lock member, and over said plate, its ends being attached to said pin, and a spring detent in said keeper member engaging said plate and serving to prevent the removal of said lock member without 90 breaking said seal.

2. The combination with a cylindrical lock member adapted to be received in a keeper when in locked position, of a pin extending from a flat face of said lock member, a disk 95 removably mounted on said pin, a seal surrounding said lock member, passing over said disk and having its ends secured on said pin, and a spring reacting against said disk away from the lock member and serving to 100 hold the seal taut.

3. The combination with a cylindrical lock member adapted to be received in a keeper when in locked position, having the usual key operated bolts for engaging said keeper, 105 and provided with a key hole in one face thereof, said face being slotted, of a pin extending from the opposite face of the lock member, a disk removably mounted upon said pin, a seal surrounding said lock member passing through slots in the outer face of the lock and over said disk, the ends of said seal engaging said pin, a boss on said seal for engaging the key hole, and spring operated means engaging said plate for holding 110 the seal taut when in assembled position.

4. The combination with a removable cylindrical lock member, and a fixed keeper shell adapted to receive said lock member, of a plate movably relatively to said lock member, and having a plurality of notches therein, a seal passing around said lock and over said plate, a spring reacting against said plate and serving to hold the seal taut, and spring detents mounted in said keeper shell, 120 and engaging said plate, the detents corresponding in number to the notches in said plate, and removed slightly therefrom.

5. The combination with a lock member and its keeper, said lock member comprising 130

a substantially cylindrical body member adapted to be engaged within said keeper when in latched position, and having a key hole on the outer face and on the inner face
5 a pin, a spring surrounding said pin, a disk on said pin beyond said spring, a plurality of spring latch members on said keeper adapted to engage said disk when the lock is engaged in its keeper; of a seal secured to
10 said cylindrical body member, passing over said key hole and said disk, and having its ends engaged with said pin.

6. The combination with a trunk lock of the swinging hasp type, and its keeper, of a
15 means for sealing the lock in latched position, said means including a sealing strip secured to the swinging hasp member, the ends thereof being covered by said member when in latched position.

20 7. The combination with a hasp, lock and its keeper, said lock comprising a fixed portion adapted to be permanently secured, and a swinging portion adapted to be engaged in said keeper when in latched position, of
25 means for sealing said swinging portion in

latched position, said means including a sealing strip surrounding said swinging member, and having its ends covered thereby when in latched position.

8. The combination with a keeper and a lock member adapted to be engaged therein in latched position, of means for sealing said lock in its keeper, said means including a sealing strip surrounding said lock member, the ends thereof being covered by said lock member and within the keeper, when the lock is in latched position.

9. The combination with a keeper and a lock member having a key hole, said lock member being adapted to be engaged in said keeper in latched position, of means for sealing said lock in latched position, said means including a sealing strip surrounding said lock member, said strip having its ends covered by said lock member when in latched position, and having a boss for engaging said key hole.

In testimony whereof I affix my signature.

OWEN M. BANGS.
